(57) CLAIM

The ornamental design for a under bed storage box, as shown and described.

DESCRIPTION

FIG. 1 is a front perspective view of a under bed storage box, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a perspective view showing the under bed storage box in a disassembled state.

The dashed lines in the drawings illustrate the portions of the under bed storage box, which form no part of the claimed design.

The dash dot lines representing stitching are part of the claimed design.
